CLAIM

The ornamental design for a portable communication device having a keypad cover, as shown and described.

DESCRIPTION

FIG. 1 is a top, front and right side perspective view of a portable communication device having a keypad cover in the closed position showing our new design;

FIG. 2 is a bottom plan view thereof;

FIG. 3 is a rear elevational view thereof;

FIG. 4 is a left side view thereof; and,

FIG. 5 is a top, front, and right side perspective view thereof with the keypad cover in the open position.

The broken line showings in FIGS. 1, 4, and 5 are for illustrative purposes only and form no part of the claimed design.
